UNITED STATES PATENT OFFICE.

CHARLES H. NORTH, OF CLEVELAND, OHIO, ASSIGNOR TO THE NORTH ELECTRIC COMPANY, OF CLEVELAND, OHIO, A CORPORATION OF OHIO.

ELECTRICAL RELAY.

972,634.

Specification of Letters Patent. Patented Oct. 11, 1910.

Application filed November 13, 1908. Serial No. 462,427.

To all whom it may concern:

Be it known that I, CHARLES H. NORTH, a citizen of the United States, residing at Cleveland, in the county of Cuyahoga and State of Ohio, have invented certain new and useful Improvements in Electrical Relays, of which the following is a specification, reference being had therein to the accompanying drawing.

10. My invention relates to electrical relays, and has for its object the improvement and simplification thereof in the manner herein-after pointed out.

In telephone and similar electrical systems, the equipments are usually built up as aggregations of small units, mounted in sets of some convenient number upon strips, bars or the like and all assembled upon convenient racks or frames. In order to facilitate wiring and also to afford access to the parts for adjustment and repairs, the relays upon these racks are usually end-supported in rows upon mounting strips. Each relay comprises an electromagnet and armature, 20 and contacts governed by the latter. There are certain requirements to be met, however, which have resulted in the gradual evolution of a peculiar type of relay especially adapted for telephonic installations 25 and for the end-mounting referred to. Among these requirements are: (1) a small lateral dimension so as to save space upon the racks; (2) simplicity and certainty in contacts and connections, and in the action 30 of the armature upon the contacts; (3) a good magnetic circuit, with a small air gap, so as to insure quickness; (4) permanent wiring connections accessible from the rear of the rack, with contact ends or points 35 and all adjustments accessible from the front; (5) capacity for several sets of make or break or make and break contacts. One type of relay hitherto produced to meet these requirements has a long core with a 40 winding upon it, a return bar connected at one end to the core and having its long limb extending parallel to the same along one side of the winding, an armature, and a number of sets of elongated German silver 45 springs with platinum points, secured on the return bar and actuated by the armature. In certain points this type of relay does not fully meet the stated requirements. For example, if a bell crank armature is employed, it has a short upper arm or lifting 50

member, so that there is no multiplication of motion between the armature end and the lifting end. Inasmuch as the springs extend forwardly from the lifting end, the latter cannot be lengthened without either engaging them at a point removed from their ends, where they are stiffer, or shortening them, and thereby losing resilience. Another point is that in all relays of this type within my knowledge, the magnet core is secured to the rear end or angle of the return bar, extending out therefrom and threaded for the purpose of securing the entire structure upon the rack. This prohibits any adjustment of the air gap by adjusting the 60 core, because to do so would necessitate taking down the entire structure.

It is the object of the invention to supply these and other deficiencies, and to provide certain new features by which the efficiency 75 of the relay is greatly increased, and it is rendered particularly suitable for use in automatic and semiautomatic telephone systems, where the response to and repetition of working impulses is required to be very 80 quick and sharp.

To attain my object I form a magnetic frame piece of a return bar with an extended longitudinal member, and bend both ends over at right angles, one serving for attachment to the mounting strip on the rack, and the other to support the magnet core and its winding. I employ a bell crank armature, but I make the vertical or magnetic member relatively short, and the horizontal or actuating member relatively long, so as to get multiplied motion at the contacts, and thus permit the air gap to be reduced. Instead of hanging this armature on the extremity 90 of the return bar, I make an opening in the latter and drop the vertical member through this opening. The contact springs are mounted on the rack end of the return bar, and extend forwardly over the armature, to the forward end thereof, by which they are 100 operated. It will thus be observed that I have contact points, the armature end, and the magnet core all accessible for purposes of inspection, adjustment and repairs. The end of the core has a detachable threaded 105 extension provided with a lock nut so that not only can the air gap be adjusted, but the electromagnet may be removed bodily without taking down the relay from the rack or disturbing the permanent wiring thereof. 110

It may be added that the terminals of the magnet windings are made in the shape of stub springs in the same sets as the contact springs, thus making the wiring uniform.

5 A great advantage of this construction lies in the fact that the length of the magnet core and spool is independent of every other dimension or part, and may be varied at will while still using standard parts otherwise.

10 My invention is illustrated in the accompanying drawings in which—

15 Figure 1 is a side view of a complete relay embodying my improvements. Fig. 2 is a front end view of the same. Figs. 3 and 4 are plan views, the former with all springs in place and the latter with all springs removed. Fig. 5 shows a modified arrangement of the return bar, with a separate mounting angle carrying the contact springs, this permitting removal of the magnet structure as a whole without detaching the springs, and also somewhat simplifying the manufacture of the parts. Fig. 6 is a 25 detail of the insulating bridge. Fig. 7 is a perspective view of the naked return bar and armature.

30 Referring to the drawings, 1 indicates the return bar, having its ends 2 and 3 both bent over at right angles to its body, the end 2 being perforated and tapped at 4 for the reception of machine screws by which it may be secured to the supporting strip on the rack, and the end 3 being centrally perforated and tapped at 5 for the reception of the threaded end of the core 6. Suitable adjusting and locking means 7 are provided for the core, which may be of any desired and suitable type. In the top of the return bar 35 1 and near the rear end thereof I produce an opening 8, the front edge of which constitutes a fulcrum for the armature. This armature is marked 9, and is provided with an integral extension arm or lever 10 bent 40 at a slightly obtuse angle, so that when the arm lies flat upon the top of the return bar as shown in Figs. 6 and 7, the armature will be slightly offset from the end of the magnet core 6. The size of the air gap is of 45 course adjustable by means of the mechanism 7, and the relative distances from the knife edge fulcrum to the center of the magnet core and to the working end of the lever 10 are such that only a very small gap is 50 required for a good working movement of the lever end. At its forward end the lever 10 is provided with lateral extensions 11 and 12, and upon this end I mount a row of studs 13, 14 and 15, for actuating the contact 55 springs. These studs should preferably be of such a length that when the armature is retracted they will not quite touch the operating springs, this being especially the case when the springs are in sets of three for 60 65 "make and break." The contact springs

may be in one, two, three or more sets. I have chosen to illustrate the standard type having three sets, indicated at 16, 17 and 18 respectively. Each of these sets is composed of three contact springs as best shown in Fig. 1, and each of the outside sets has in addition a stub spring 19 attached to one end of the winding 20 on the core 6, and constituting a terminal therefor. The springs are separated by insulating slips 21, and each set is fastened by means of screws 22 and an overlying metal washer 23 to a U-shaped mounting plate 24, which is secured to the return bar preferably by screws 25 inserted from beneath. This method of mounting enables me to assemble all the springs as a unit on the plate 24 and to attach the same to and remove them from the relay at will, without disturbing the rest of the structure. The plate 24 has an additional function, in that it covers the opening 8 of the return bar, and keeps the armature in position. It is so proportioned that when attached to the return bar the front edge of its body (marked 26 in Fig. 4), lies parallel to the knife edge, with just enough space for the passage of the armature lever; while its projecting members 27 and 28 lie on both sides of the lever 10. The thickness of the plate 24 is not less than the thickness of the 90 armature lever, the springs being thus raised above the latter.

Near the forward end of the return bar is mounted a bridge 29, shown in Figs. 1, 2, 3 and 6. This has an opening 30 in which the lever 10 plays, and openings 31 for the passage of the contact springs, one for each set. The bridge is attached to the bar preferably by screws inserted from beneath as indicated at 32 in Fig. 1. It serves both as a guide and limiting stop for the armature lever and as a support and stop for the several contact springs. Thus, referring to Fig. 1, the lower spring 16^a is given a downward set which causes it to press against the lower edge of the opening 31, spring 16^c is similarly given an upward set which springs it against the upper edge of the opening, and 110 16^b is given a downward set so that it normally rests in contact with 16^a. The bridge 115 is set far enough back from the ends of the springs so that the latter may yield slightly, thus avoiding absolutely solid contacts, which would be bad practice, and necessitate difficult adjustments where the actuating 120 part is common to them all.

In Fig. 5 I have shown a modification in which the member 2 and the plate 24 are combined in one angle piece separate from the return bar 1. By removing the screws 125 25 or any equivalent fastening devices that may be employed, the parts 1, 3, 6, 7, 9, 10, 13, 14, 15 and 20 may be removed from the front, without disturbing the springs and their connections on the rack. An addi- 130

tional advantage is that a magnet and return bar of any desired length may be employed, without changing the dimensions or arrangements of the springs or their mounting plate 24, so long as the lever 10 has its studs set properly to engage the ends of the springs. If the magnet structure is made longer than that shown in Fig. 1, its extension would be in a forward direction, that is to say toward the left in Fig. 1, the distance between the member 2 and the knife edge fulcrum for the armature being preferably kept constant. With the construction shown in Fig. 5, since the member 2 is separate, the opening 8 in the rear end of the return bar is reduced to a slot which facilitates the introduction of the armature. Various changes may be made in details of construction in this relay without departing from the spirit of my invention, such for example as using two magnet spools with parallel cores forming a so-called horseshoe or double pole magnet, instead of a single magnetic element such as I have described. I believe I am the first to make a relay of this type with a bell crank armature fulcrumed at the rear instead of the front end of the magnet, so as to bring the butt of the magnet core to the front; also that I am the first to pivot or fulcrum the actuating lever at a point adjacent to the point of support of the springs, extending it substantially parallel therewith and connecting it thereto at its end whereby a long leverage is obtained without increasing the total length of the structure beyond that required by the dimensions of the springs themselves. I shall therefore claim these features broadly, and wish it clearly understood that I contemplate all non-essential changes or modifications which come fairly within the scope of the invention defined in the appended claims.

Having thus described my invention what I claim and desire to secure by Letters Patent is—

1. A relay comprising an electromagnet, contact springs mounted upon the magnet structure, an armature lever pivotally supported at a point adjacent the mounting of the springs, an operative connection between the free end of the lever and the springs, and an armature connected to the lever and extending across an exposed pole of the electromagnet adjacent the pivotal support, whereby a small air gap and multiplied motion of the free end of the lever are secured.

2. In a relay, a magnetic core carrying a winding, a magnetic return bar extending parallel to the core, contact springs secured upon the return bar and extending along the same parallel with the magnet core, an armature lever pivotally mounted upon the return bar at a point adjacent to the spring

mounting, and extending along the bar to a point adjacent the ends of the springs, and an operative connection between the lever and the springs.

3. In a relay, an electromagnet, a return bar therefor, contact springs thereon, an armature lever of approximately the same length as the springs, mounted on the bar so as to extend in the same direction as the springs, and an operative connection between the ends of the bar and the springs. 70 75

4. In a relay, an electromagnet, a relatively short armature adjacent an exposed pole of the magnet, contact springs, and an extended armature lever for operating the same, said springs and lever having adjacent points of support and parallel motion in operation. 80

5. A relay comprising an iron return bar, a magnet core mounted upon the front end 85 of the bar and extending rearwardly parallel to the same, contact springs and an armature lever mounted upon the rear end of the return bar and extending forwardly, a winding upon the core, and an operative 90 connection between the forward ends of the lever and springs.

6. A relay having elongated contact springs and a correspondingly elongated operating lever therefor, mounted so as to have parallel motion, and a relatively short armature working on a small air gap, said lever and armature being so related and connected that the movement of the armature will be multiplied when communicated to 100 the springs. 95

7. A relay comprising an electromagnet structure having an adjustable core, contact springs having free adjustable tips, a bell crank armature and its lever with means 105 thereon for actuating the springs, and a winding for the electromagnet, all of the fixed elements being secured upon one end of the structure and all of the adjustable elements accessible at the other. 110

8. A relay having an electromagnetic frame or return bar, a core adjustably mounted upon one end of said bar and extending parallel therewith, contact springs and an armature mounted at the other end of said bar, a winding upon said core, and an actuating lever connected to the armature and extending along the bar parallel to the springs, with an actuating connection adjacent the ends thereof. 115 120

9. A relay adapted for end-support comprising an elongated return bar having both ends bent at an angle to the body, means for attaching the rear end to a support, a core adjustably attached to the front end, and extending parallel with the body, a winding on said core, contact springs secured upon the body adjacent to the rear end thereof and extending parallel therewith, an armature mounted adjacent to the rear end of the 130

body, an actuating lever connected thereto and extending parallel to the springs, and an operative connection between said lever and springs adjacent to the front end of the body.

- 5 10. A relay comprising the following instrumentalities: an elongated frame or return bar having both ends bent over at substantially right angles, a core adjustably secured to the front end, and extending parallel with the bar for a portion of its length, so as to leave an open space between the rear end of the core and the rear bent end of the frame, a bell crank armature and lever extending through an opening adjacent the rear end of the frame and fulcrumed on the front edge of said opening with the armature extending downwardly into juxtaposition with the end of the core and the lever extending along the body of the frame, a mounting plate secured upon the rear end of the frame over the said opening, so as to cover the same and prevent displacement of the armature, contact springs mounted upon but insulated from said plate, and extending forwardly along the frame parallel to the armature lever, and an insulating connection between the forward ends of the armature lever and the springs.
- 15 20 25 30 11. A relay comprising the following instrumentalities: an elongated frame or return bar having both ends bent over at substantially right angles, a core adjustably secured to the front end, and extending par-

allel with the bar for a portion of its length, so as to leave an open space between the rear end of the core and the rear bent end of the frame, a bell crank armature and lever extending through an opening adjacent the rear end of the frame and fulcrumed on the front edge of said opening with the armature extending downwardly into juxtaposition with the end of the core and the lever extending along the body of the frame, a mounting plate secured upon the rear end of the frame over the said opening, so as to cover the same and prevent displacement of the armature, contact springs mounted upon but insulated from said plate, and extending forwardly along the frame parallel to the armature lever, and an insulating connection between the forward ends of the armature lever and the springs, together with a bridge of insulating material mounted upon the frame and provided with openings for the said lever and springs, forming a guide therefor and stops for the springs.

12. A relay having a frame or return bar, contact springs and an actuating lever mounted thereon, and a bridge also mounted thereon and provided with openings for the passage of the lever and springs.

In testimony whereof I affix my signature in presence of two witnesses.
